UNITED STATES PATENT OFFICE.

HENRY C. COLEMAN, OF LAWRENCEBURG, TENNESSEE.

FLUE SCRAPER.

Application filed August 23, 1923. Serial No. 658,886.

This invention relates to a flue scraper and has for its principal object to provide a simple and efficient means which is especially adapted for use in connection with removing soot from the inner walls of a stove pipe while the same is connected to the stove and chimney, thus obviating the necessity of having to remove the stovepipe from its position whenever it is necessary to clean the same.

Another important object of the invention is to provide a flue scraper of the above mentioned character, which is of such construction as to enable the same to be extended to various lengths thereby enabling the same to be used in connection with stovepipes of various lengths.

A further object of the invention is to provide a flue scraper of the above mentioned character, which does not interfere with the passage of smoke through the chimney and will also prevent the possibility of causing the dust or soot to escape through the stovepipe and enter the room.

25 A further object of the invention is to provide a flue scraper which is simple in construction, inexpensive, strong, durable and further well adapted for the purpose for which it is designated.

30 Other objects and advantages of this invention will become apparent during the course of the following description.

In the accompanying drawings forming a part of this specification and in which like numerals designate like parts throughout the same:—

Figure 1 is a sectional view of a horizontally arranged stovepipe and the usual elbow associated therewith at one end and showing 40 my improved flue scraper in position for use therein.

Figure 2 is a plan view of my flue scraper.

Figure 3 is a view showing the extension adapted to be associated with my flue 45 scraper when it is desired to lengthen the same.

In the drawings wherein for the purpose of illustration is shown the preferred embodiment of my invention, the numeral 1 50 designates the horizontal section of a stovepipe of the ordinary construction and is provided with the usual elbow 2, it being understood that this pipe is connected up to the stove and chimney in the well known manner. The elbow 2 is provided with an

opening 3 therein and adapted to extend through this opening is the elongated rod 4. The outer end of this rod 4 is coiled around itself as shown at 5 in the drawings to provide a suitable operating handle 6. The inner end of the rod 4 is provided with the looped portions 7 and 8 in the manner as more clearly shown in Figs. 1 and 2 of the drawings and the purpose of this construction will be hereinafter more fully 65 described.

Slidably and adjustably supported in the looped portions 7 and 8 of the elongated rod 4 is the inner end of a scraper blade supporting rod designated by the numeral 9. The outer end of this supporting rod 9 is offset as shown at 10 in the drawings and a short section or piece of wire 11 has one end coiled around the rod 9 adjacent the offset portion 10 in the manner as clearly shown at 12 in 75 the drawings. The purpose of such an arrangement is to provide a pair of diverging arms at the outer end of the supporting rod 9 and is clearly shown in Fig. 2 of the drawings.

The outer free ends of the arms 10 and 11 are adapted to be bent back upon themselves and provide a means for pivotally supporting the scraper blade 13 and this scraper blade 13 extends transversely across the inner free ends of the arms 10 and 11. The scraper blade 13 is provided with a curved scraping edge 14 which is adapted to cooperate with the inner wall of the flue pipe 1 when in use.

As stated above, the rod 9 is slidably and adjustably received in the looped portions 7 and 8 of the elongated rod 4. It may be here stated that this rod 9 is frictionally engaged with these looped portions and the inner free end of said rod 9 is bent around the loop 7 as clearly shown in Fig. 2 of the drawings. When it is desired to shorten the 95 device this device the rod 9 may be forced longitudinally along the rod 4 through the looped portions 7 and 8.

In Fig. 3 of the drawings there is shown the rod designated by the numeral 15 and this rod 15 is provided at its forward end with a pair of loops 16 and 17 respectively in a manner similar to the looped portions 7 and 8 provided on the inner end of the elongated rod 4. This rod 15 is adapted to be associated with the supporting rod 9 and the elongated rod 4 when it is desired 110

to extend the length of the scraper blade supporting rod in order to accommodate its use to a long section of stovepipe. The extending of the supporting rod 9 with relation to the elongated rod 4 is accomplished by inserting the lower end of the rod 15 in the looped portions 7 and 8 thereof and having the looped portions 16 and 17 respectively of the rod 15 adapted to slidably 10 and adjustably receive the lower end of the supporting rod 9. In this manner the various rods may be extended and held in their proper adjusted position by means of the frictional engagement of the looped portions with the respective portions of the rods supported therein.

In applying the extension member, shown in Fig. 3, to the device as shown in Figs. 1 and 2, the end of the rod 15 opposite 20 that having the loop 17 formed thereon is adapted to be engaged and bent around the loop 7 of the rod 4 in a manner similar to the showing in Fig. 2, wherein the end of the rod 9 is engaged with said loop. In 25 other words, this rod 15 is merely an insertable extension to be placed between the rods 4 and 9 when the scraper is to be used in a pipe of extended length.

With the parts arranged as shown in Fig. 30 1 of the drawings, by pulling outwardly on the handle 6 the scraper blade 13 will be caused to have its curved scraping end 14 scrape along the bottom of the stovepipe 1 and cause the soot which has collected on 35 the inner walls of the stovepipe to be carried forwardly and discharged into the stove where it is burned. When not in use the coiled portion 5 will fit in the opening 3 provided in the elbow 2 and thereby prevent the possibility of any smoke being discharged from the stove from entering the room.

The simplicity of my flue scraper enables 40 the same to be readily and easily operated and does not require the necessity of having to remove sections of stovepipe from 45 their proper positions in order to accomplish the desired results. It is to be further understood that when the scraper is in 50 an inoperative position, the blade is so arranged as to permit the smoke to pass

through the stovepipe without being obstructed.

From the foregoing description of the construction of my improved apparatus, it 55 will be seen that I have provided a simple, inexpensive and efficient means for carrying out the objects of the invention, and while I have particularly described the elements best adapted to perform the functions 60 set forth, it is obvious that various changes in form, proportion and in the minor details of construction may be resorted to without departing from the spirit or sacrificing any of the principles of the invention. 65

What I claim as new and desire to secure by Letters Patent is:—

1. A flue scraper comprising a rod, the outer end thereof forming a handle, the inner end of said rod being provided with 70 looped portions, a supporting rod slidably and adjustably mounted in said looped portions, and a scraper blade carried by the outer end of said supporting rod.

2. A flue scraper comprising a rod, the outer end thereof forming a handle, the inner end of said rod being provided with spaced looped portions, a supporting member slidably and adjustably mounted in said looped portions, the outer end of said supporting member being provided with diverging arms, and a scraper blade connected to the free ends of said arms. 75 80

3. A flue scraper of the class described comprising an elongated rod having its outer end provided with a handle, the inner end of said elongated rod being provided with spaced looped portions therein, a scraper blade supporting rod having its inner end slidably and adjustably received in 85 said looped portions, the outer end of said supporting member being offset, a piece of wire having one end coiled around said supporting member at the offset portion thereof to provide a pair of diverging arms at 90 the outer end of said supporting member, and a scraper blade extending transversely across the free ends of said arms and pivotally mounted thereon. 95

In testimony whereof I affix my signature. 100

HENRY C. COLEMAN.
